UNITED STATES PATENT OFFICE.

CHARLES MOSER ZIMMERMAN, OF CINCINNATI, OHIO.

GLUE-FAUCET.

971,337.

Specification of Letters Patent. Patented Sept. 27, 1910.

Application filed May 31, 1910. Serial No. 564,111.

To all whom it may concern:

Be it known that I, CHARLES MOSER ZIMMERMAN, a citizen of the United States, and a resident of Cincinnati, in the county of Hamilton and State of Ohio, have invented 5 a new and Improved Glue-Faucet, of which the following is a full, clear, and exact description.

Heretofore molasses faucets have been 10 generally used on glue kettles. They are, however, unsatisfactory as the valve frequently sticks and requires a very strong pull to unseat it. This often results in breaking the faucet, and sometimes causes 15 the faucet to be torn from the kettle, or the kettle torn from the stand.

I have designed a faucet in which the foregoing objections are substantially overcome, and in which the force incident to the 20 opening of the valve, reacts against the vessel, ordinarily through the valve housing or mounting.

Reference is to be had to the accompanying drawings forming a part of this specification, in which similar characters of reference indicate corresponding parts in both the views.

Figure 1 is a central vertical section of a 30 glue faucet constructed in accordance with my invention as applied to the glue kettle; and Fig. 2 is an inverted plan of the faucet, partly in section, and with the valve open.

The faucet in its preferred embodiment comprises a valve cylinder or housing 5, 35 which is provided at its forward edge with an external shoulder or flange 6. From the top of this flange an arm 7 extends outwardly and is offset or turned downwardly at its free end, as indicated at 8. At the 40 bottom of the flange 6, a drain spout 9 inclines downwardly and outwardly, both the arm 7 and drain spout 9, as also the valve cylinder 5, being preferably cast or otherwise formed in a single piece. Within the 45 valve cylinder 5 is slidably fitted a thimble valve 10, which, at its outer end or portion, is provided with a flange or shoulder 11, arranged to bear against the valve seat afforded by the front face of the flange 6. 50 The upper portion of the flange 11 is bifurcated or slotted, as indicated at 12, to receive the arm 7, and in this manner prevent the valve from turning in the valve cylinder. The body of the valve intermediate 55 its length and at the bottom is provided with a discharge opening 13. The body of

the valve cylinder is externally threaded at its smaller end to receive a clamping ring 14, which, at its inner portion, is expanded or flanged and formed to bear on its outer edge 15 only, the diameter of this bearing edge being ordinarily equal to or slightly less than the diameter of the flange 6, so that when the faucet is applied to the kettle, as shown in the drawing figures, the metal 60 of the vessel will be forcibly bound between the clamping ring and flange 6, and a fluid-tight joint formed therebetween.

Journaled or swiveled in the closed or flanged outer end of the thimble valve, is a valve stem 16, the connection between these two parts being ordinarily effected by passing the reduced inner end of the stem through a central opening formed in the outer wall of the valve, and riveting or expanding the inwardly-extending portion of the stem to form a shoulder or head 17, the stem being free to turn in the valve between this shoulder and the shoulder presented by the reduced portion of the stem, so that the 70 stem and valve can revolve relatively to each other, but are enforced to travel together in a longitudinal direction. The 75 outer portion of the stem is preferably screw-threaded and threads through the off-set end 8 of the arm 7, at the front of which it is provided with a suitable handle 18.

With the faucet thus constructed, when the valve is in the closed position shown in Fig. 1, the glue or other fluid is effectively 80 cut off. By, however, turning the handle 18 in a direction to draw the stem outwardly, the valve is drawn from the valve cylinder and is guided along the arm. As the discharge opening 13 passes to the outside of 85 the cylinder, the glue is free to flow from the vessel through the tubular inner end of the valve, and the discharge opening 13, from which it falls on the spout 9, the spout 90 discharging the glue from the side of the vessel to any receptacle placed to receive the glue. It will be noted that the construction is such that the force required to unseat the valve, through the arm 7, reacts against the valve cylinder or housing and the glue 95 kettle, making it impossible to loosen the faucet from the kettle or tear the kettle from the stand in opening the valve. The construction is also such that it is impossible 100 for the valve to adhere to its seat sufficiently 105 to cause the faucet to be broken in drawing the valve from the valve cylinder.

Having thus described my invention, I claim as new and desire to secure by Letters Patent:

1. A faucet comprising a valve cylinder, an arm extending outwardly from the cylinder, having an offset end, a valve guided on the arm and slidably into and out of the cylinder, a valve stem passing through the offset end of the arm and operatively connected to the valve, and means to positively move the stem to and from its seat, reacting against the offset end of the arm.
2. A faucet comprising a tubular member having a valve seat, a support extending outwardly from the member, a valve slidably engaged with the support and adapted to bear against the seat of the tubular member and cut off the flow therethrough, a valve stem having a swiveled connection with the valve and threaded through the support, and means at the outside of the support to operate the stem.
3. A faucet comprising a valve cylinder, a thimble valve slidable in the cylinder and held from turning therein and having a discharge opening at the lower side, an arm extending outwardly from the cylinder, having an offset portion, a valve stem operatively connected to the valve and passing through the offset portion of the arm, and means to move the stem of the valve longitudinally to carry the valve to and from its seat, reacting against the said arm.
4. A faucet comprising a valve cylinder having an outwardly-extending arm provided with an offset outer portion, a thimble valve slidable in the cylinder and slidably engaged with the arm, having a discharge opening at the bottom, a drain spout extending from the lower outer portion of the cylinder, a valve stem having a swiveled

connection with the valve and threaded through the offset portion of the arm, and a handle connected to the valve stem at the outside of the arm.

5. A faucet comprising a valve cylinder having an external flange at its outer end, an arm extending from the upper portion of the flange, having an offset end portion, a drain spout extending from the lower portion of the said flange, a clamping ring threaded on the body of the valve cylinder and adapted to bind the vessel to which the valve is applied, to the shoulder presented by the flange, a valve slidable in the valve cylinder, having a discharge opening at the lower side thereof and slidably engaged with the arm, a valve stem threaded through the offset portion of the arm and having a swiveled connection with the valve, and an operating member connected to the stem at the outside of the arm.

6. A faucet comprising a tubular member having a valve seat, an arm extending outwardly from the upper portion of the member, having an offset outer portion, a drain spout extending from the lower portion of the member, a valve arranged to seat against the said member and held from turning relatively thereto, a valve stem passing through the offset portion of the arm and operatively connected to the valve, and means to move the valve stem longitudinally, reacting against the arm.

In testimony whereof I have signed my name to this specification in the presence of two subscribing witnesses.

CHARLES MOSER ZIMMERMAN.
